UNITED STATES PATENT OFFICE.

REBECCA SMITH, OF NEW YORK, N. Y., ASSIGNOR TO JOSEPH F. PUGLIESE.

WASHBOILER.

Application filed October 21, 1926. Serial No. 143,073.

This invention relates generally to wash boilers used for washing clothes and the like, the invention having more particular reference to a novel type of double wash boiler.

5 The invention has for an object the provision of an improved double wash boiler of novel construction and arrangement of parts.

10 For further comprehension of the invention, and of the objects and advantages thereof, reference will be had to the following description and accompanying drawing, and to the appended claims in which the various novel features of the invention are more 15 particularly set forth.

Fig. 1, of the drawing, is a top plan view of my improved double wash boiler.

Fig. 2, is a longitudinal central sectional view taken on the line 2—2 of Fig. 1.

20 Fig. 3, is a transverse central sectional view taken on the line 3—3 of Fig. 1.

Fig. 4, is a fragmentary sectional view taken on the line 4—4 of Fig. 3.

As here embodied my improved double 25 wash boiler comprises an outer receptacle 10, adapted to hold or contain water, preferably of oval shaped hollow construction. The receptacle 10 has attached thereto, handles 11.

30 The inner receptacle 12, of similar construction to the above mentioned outer receptacle 10, is of suitable size to be placed inside the receptacle 10, so as to provide spaces 13 and 14, at the ends and sides, respectively of the inner receptacle 12. The inner receptacle 12 is perforated, as at 15, by a plurality of apertures formed therein, and positioned relatively adjacent to the bottom of the inner receptacle 12. The above described 35 construction being such as will permit the clothes or the like, to be boiled, and which are placed in the inner receptacle 12, to be saturated by the water placed in the receptacle 10, when the inner receptacle 12 is lowered in the receptacle 10.

The crank 16, provided with a handle element 17, is rotatively mounted in the receptacle 10, and has attached thereto, a bevel pinion 18, meshing with the bevel pinion 19, attached to the screw shaft 20. The screw shaft 20 is rotatively mounted in extended elements or lugs 21 and 22 of the receptacle 10, located adjacent to the top and bottom, respectively of the receptacle 10. The bevel pinion 23 is attached to the screw shaft 20, and meshes with a bevel

pinion 24, attached to the shaft 25, rotatively mounted in the extended elements 22' of the receptacle 10. The bevel pinion 23 is attached to the shaft 25, and meshes with the bevel pinion 27 attached to the screw shaft 28, rotatively mounted in the extended elements or lugs 21' and 22' of the receptacle 10.

It being understood that the said extended 60 elements 21' and 22' are located adjacent to the top and bottom of the receptacle 10, directly opposite to the said extended elements 21 and 22, at the ends of the said receptacle 10. The ring member 29, oval 70 shaped, is attached to the bottom of the inner receptacle 12, and has attached thereto and extended therefrom, support members 30, provided with apertures adapted to slidably engage the guide rods 31 and 32, attached to the extended elements 21 and 22, and to the extended elements 21' and 22', of the receptacle 10. The support members 30, are provided with a threaded aperture, 75 adapted to engage the screw shafts 20 and 28.

The above described construction being such as will permit the inner receptacle 12, to be lowered into, or raised from the receptacle 10, when the crank 16 is turned or 80 rotated by means of the handle element 17.

The door 33, is provided with a recessed portion 34, and has attached thereto, a handle 35, extended over the recessed portion 34. The door 33 is slidably positioned in the one 90 side of the inner receptacle 12, and is adapted to slidably engage in the groove 36, formed in the inner receptacle 12, adjacent to the opening formed therein to accommodate the said door 33. The latter described 95 construction being such as will permit the clothes, desired to be placed in, or removed from the inner receptacle 12, to be readily removed from the said inner receptacle 12, when the said inner receptacle 12 is in a 100 raised position.

The cover 37, is adapted to slidably engage inside the inner receptacle 12, so as to enclose or cover the said inner receptacle 12, and has pivotally attached thereto a 105 handle 37'. The cover 37 has slidably attached thereto, catch members 38, provided with handle elements 39. The catch members 38, are adapted to slidably engage apertures 40, formed in the C shaped members 110 41, attached to the inner receptacle 12, and extended therefrom, so as to permit the

cover 37, to be held in any desired position in the inner receptacle 12, as may be desired, depending upon the quantity or amount of clothes, or the like, placed in the said inner receptacle 12.

The cover 42, is adapted to enclose, or cover the receptacle 10, when the inner receptacle 12, is in a lowered position, so as to prevent the escape of steam from the receptacle 10 and the inner receptacle 12.

While I have above described the preferred form, construction and arrangement of the several elements employed, it will be understood that the device is, nevertheless, susceptible of considerable modification therein, and I therefore reserve the privilege of resorting to all such changes as may be fairly embodied with the spirit and scope of the invention as claimed.

Having thus described my invention, what I claim as new and desire to protect by Letters Patent of the United States is as follows:—

1. In a device of the class described, the combination with an outer receptacle, of an inner receptacle having an opening in one side; there being a groove provided adjacent the opening, a door with a handle, slidably engaged in the groove for upward and downward movements and forming a closure for

said opening, and means for hoisting the inner receptacle with respect to the outer receptacle so that with the inner receptacle in a raised position, clothes within the inner receptacle may be removed through the said side opening by raising the said door.

2. In a device of the class described, the combination with an inner receptacle, of an outer receptacle provided on its inner side with lugs near the top and bottom thereof, screw shafts rotatively and vertically mounted in the lugs, a bevel gear secured to the upper end of one of the screw shafts, a crank mounted in the outer receptacle, a bevel pinion secured to one end of the crank, and meshing with the bevel gear, other bevel gears secured to the lower ends of the screw shafts, a shaft horizontally mounted in the lower lugs, bevel pinions on the last mentioned shaft, meshing with bevel gears on the lower ends of the screw shafts, guide rods attached to the lugs, support members slidably mounted on the guide rods, and threadedly engaging the said screw shafts, and means attached to the bottom of the inner receptacle and connected to the support members.

In testimony whereof I have affixed my signature.

REBECCA SMITH.
